UNITED STATES PATENT OFFICE.

ELISHA MOORE, OF MEDUCTIC, CANADA.

MECHANISM FOR IMPARTING SUCCESSIVE OR ALTERNATING MOVEMENTS.

SPECIFICATION forming part of Letters Patent No. 611,501, dated September 27, 1898.

Application filed February 3, 1898. Serial No. 669,012. (No model.)

To all whom it may concern:

Be it known that I, ELISHA MOORE, a subject of the Queen of Great Britain, residing at Meductic, in the county of York and Province of New Brunswick, Canada, have invented certain new and useful Improvements in Mechanism for Imparting Successive or Alternating Movements, of which the following is a specification.

10 The object of my invention is to produce an alternating or reciprocating movement by successive pulls or impulses—such, for instance, as produced by repeatedly energizing an electromagnet.

15 With these ends in view my invention consists in the parts and combination of parts, as will be hereinafter more fully described, with reference to the accompanying drawings, wherein for purposes of illustration it is 20 associated with a tramway-switch.

In said drawings, Figure 1 is an inverted plan view of my improvement. Fig. 2 is a perspective view of the same. Fig. 3 is a sectional view through the switch-box and a portion of a car with the operating mechanism in position. Figs. 4, 5, and 6 are detail views of the operating mechanism. Fig. 7 is a perspective view of the switch-tongue. Fig. 8 is a plan view of a track and switch, showing the relative position of contact-plate and switch-tongue. Fig. 9 is a perspective view of a slight modification. Fig. 10 is a reverse view of the ratchet-wheels and the co-operating dogs. Fig. 11 is a view of the magnets. 35 1 represents the main-track rails, 2 the switch-rails, and 3 the car.

40 4 is the switch-box, located between the rails of the main track at the juncture of the switch, suitably cased with brickwork. 5 is the covering for said box, of suitable material, which is secured in place by means of suitable bolts 6.

45 7 are integral depending lugs extending from the under side of the plate 5.

8, 9, and 10 are ratchet-wheels cast integrally and provided with a suitable axis 11 and 12, having the collars 13 and 14. The teeth on wheels 8 and 9 are cut so as to alternate—that is to say, the teeth on wheel 8 alternate with those on wheel 9. Wheel 10 is

formed with twice the number of teeth that wheels 8 and 9 have.

15 16 are depending lugs integral with the cover 5, between which is pivoted a dog 16, on the top of which is formed a groove 17, in 55 which one end of a pressure-spring 18 is adapted to slide. The other end of this spring 18 is rigidly secured to the cover 5.

19 is a depending lug on the bottom of the cover 5.

20 21 is the switch-tongue, provided at its rear end with a pivot-pin 21, a portion of which, as at 22, is round in cross-section, while at 23 it is rectangular. The extreme end of the pin is screw-threaded. The pin 21 is passed 65 through an opening in the cover 5 and the lug 19, the round portion 22 extending a distance equal to the thickness of said cover and lug, the square portion 23 extending above the lug. 70

24 is a cross-arm provided with a rectangular opening adapted to fit over the portion 23 of the pin and secured in place by means of the nut 25.

25 26 and 27 are U-shaped springs to one end 75 of each of which is secured a dog 28, from one side of which extends a slotted plate 29. The dogs 28 are adapted, respectively, to engage the ratchet-wheels 8 and 9, while the slotted plates are adapted, respectively, to engage the axes 11 and 12. 30 are arms bolted or otherwise suitably secured to the other and longer end of the springs 26 and 27, respectively. These springs are pivoted to cross-arm 24. 85

31 is an arm pivoted at 32 to the under side of the cover 5, which extends through the U-shaped bracket 33, secured to the cover.

34 is a thumb-screw passing through the yoke of the bracket and adapted to control 90 the swinging movement of the arm 31.

35 is a spring one end of which is secured to the cover, while the other end is in engagement with the free end of the arm 31 and adapted to hold said arm normally up against 95 the under side of the cover.

36 is a side lug integral with the arm 31, to which is pivoted a dog 37, the top of which is grooved at 38, in which the free end of spring 39 is adapted to slide. The other end 100

of this spring is secured to the arm 31 at 40. This dog 37 is adapted to engage the ratchet-wheel 10.

50 is an armature rigidly secured to the 5 arm 31.

51 is the magnet suitably secured in the switch-box immediately below the armature 50.

52 are suitable binding-posts, and 53 53^a 10 are insulated contact-plates located between the rails of the main track a suitable distance from the switch. An actuating-conductor 59 extends from insulated contact 53^a through a source of electricity 59^a, through magnet 51 15 and back to contact-plate 53.

54 is a contact-arm hung in suitable brackets under the car 3 and provided with contact-point 55, preferably composed of a roller adapted to contact with the contact-plate 53. 20 56 is a weight secured to the other end of the contact-arm.

57 is a foot bell-crank lever secured to the platform of a car and connected to the contact-arm by means of a chain or rod 58, as 25 best seen in Fig. 3.

The operation is as follows: The car 3 approaching the switch pressure is applied to the bell-crank lever 57 by the motorman, thus throwing the contact-point 55 down upon the 30 bed of the track, whereupon it engages or makes contact with the contact-plates 53 53^a, thus establishing a circuit through the wires to the magnets 51, whereupon the armature is attracted toward the magnet and held as 35 long as the circuit is completed, thus drawing down the arm 31, which through dog 37 moves the ratchet-wheel 10 one tooth, the retaining-dog 17 holding the ratchet-wheel after it is moved against backward movement.

40 This movement of the ratchet-wheel 10 carries both of the ratchet-wheels 8 and 9 simultaneously, the dogs 28 slipping over the teeth of the wheels 8 and 9. In this movement one of the dogs 28 slips into engagement with the 45 teeth on the ratchet-wheel 9. The spring-yoke following the inward movement of the tooth pulls the cross-arm 24 through the arm 30, thus throwing the switch-tongue over against the rail of the main track, thus opening the 50 switch. If it is desired that the next car pass by the switch on the main track, the contact-point 55 is thrown into engagement with the plate 53, thus establishing the circuit, whereupon the armature is again attracted to the magnets, thus again operating the ratchet-wheels 10, 9, and 8, and the other 55 spring-yoke is thrown into engagement with the teeth of the ratchet-wheel 8, thus turning the cross-arm 24 by the pull on the arm 60 30 and throwing the switch-tongue over, thereby leaving the main track clear. The spring 35 always returns the armature and its carrying-arm 31 back to a normal position up against the under side of the cover 5.

65 The ratchets on the ratchet-wheels 8 and 9 are cut so as to alternate with each other, and

the ratchet-wheel 10 is provided with twice the number of teeth as are on the ratchet-wheels 8 and 9. Thus when the ratchet-wheel 10 is moved one tooth by the dog 37 the 70 ratchet-wheels 8 and 9 are only moved a distance equal to half that between their teeth. As the teeth on these latter wheels are cut to alternate, it will be seen that only one of the dogs 28 will be in engagement with the alternating teeth at a time—that is to say, when the dog 28 on one of the U-shaped springs 27 is in full engagement with a tooth on, say, ratchet-wheel 9 the other dog 28 is not in positive engagement with the teeth on the wheel 80 8, but is merely in idle contact with the same ready to snap into the next tooth when the armature is next attracted to the magnets. The backward and forward sliding motion of these dogs 28 is guided by means of the slot-85 ted plates in engagement with the axes 11 and 12.

From the foregoing it will be seen that by reason of the construction of the ratchet-wheels 10, 8, and 9 and the spring-pawl 28 90 with their connection to the switch-tongue it is only necessary to employ a single magnet to operate the switch. The binding-posts 52 are placed in the switch-box merely for convenience in disconnecting the magnets 95 from the contact-plate 53 and circuit 59.

It will be seen that by reason of the resiliency of the yokes 26 and 27 and their connection through the arms 30 with the switch-tongue said tongue can be knocked out by a 100 car going in the opposite direction without operating the train of ratchet-wheels. This obviates the use of certain springs and the necessity of setting the switch each time.

In Fig. 9 I have shown a slight modification 105 of the yokes, in which 24^a is the cross-arm, pivoted as described, from which extend two spring members or yokes 26^a 27^a, coiled near their center, as at 62. 63 is a bracket secured to the cover 5 by means of suitable bolts and 110 provided with a cross-arm 64, on which the spring-yokes are mounted by means of the coils 62. The operation of this construction is the same as that described in connection with the yokes 26 and 27. 115

What I claim is—

1. The combination with a shifting member, of a train of alternately-operating wheels, dogs coöperating with said wheels, means connecting the dogs with the shifting 120 member and means for operating the whole.

2. The combination with a shifting member, of a train of integral ratchet-wheels with teeth cut to alternate, dogs coöperating with said wheels, and means connecting the dogs 125 with the shifting member, and a magnet with its armature suitably connected to operate the whole.

3. The combination with a shifting member, of a train of integral ratchet-wheels provided with teeth cut to alternate, a dog engaging one of said wheels, a magnet with its 130

- armature, means connecting said dog with said armature, dogs coöperating with the other ratchet-wheels, and means connecting the latter dogs with the shifting member.
- 5 4. The combination with a shifting member of a train of integral ratchet-wheels each provided with teeth cut to alternate with the teeth on the other wheel, a dog coöperating with one of said ratchet-wheels, a magnet having operative connection with said dog, dogs resiliently mounted and coöperating with the other two ratchet-wheels, and means for connecting the said dogs with the shifting member, substantially as described.
- 15 5. In an electric switch, the combination with the switch-tongue, of resilient yokes connected with said tongue, dogs mounted respectively on one end of said yokes, integral ratchet-wheels having their respective teeth cut to alternate, and adapted to engage the dogs on the said yokes, and means for operating said ratchet-wheels, substantially as described.
- 25 6. In an electric switch, the combination with the switch-tongue, of integral ratchet-wheels cut with teeth to alternate respectively, coöperating dogs, resilient yokes connecting said dogs with said tongue, and a magnet with its armature connected with said ratchet-wheels; substantially as described.
- 35 7. The combination with a train of integral ratchet-wheels and their coöperating dogs, one of said wheels having a greater number of teeth than the other two, and means for connecting the dog of the last-named ratchet-wheel with a suitable source of power and means for connecting the first-named ratchet-wheels with a member to be operated, substantially as described.
- 40 8. The combination with a train of integral ratchet-wheels, one of which has a greater number of teeth than the other two, of resiliently-mounted dogs adapted to engage the other two ratchet-wheels alternately, and a slotted plate connected to said dogs and adapted to have bearing and slide on the axis of said train of wheels, substantially as described.
- 45 9. In an electric-railway switch, the combination with the switch-tongue, resilient yokes connected with said tongue, dogs mounted on one end of the respective yokes of a train of integral ratchet-wheels with teeth cut to alternate, another integral ratchet-wheel, an operating-dog engaging the same, and means to operate said dog, substantially as described. 55
10. In an electric-railway switch, the combination with the switch-tongue, a cross-arm rigidly connected with said switch-tongue, of spring-yokes, one end of which is connected to said cross-arm, a dog and a slotted plate secured to the other ends respectively of said yokes, a train of ratchet-wheels with teeth cut to alternate, said dogs adapted to alternately engage said ratchet-wheels and guided in their engagement by the slotted plate working on the axis of said train of wheels of another ratchet-wheel having a greater number of teeth than the train of wheels, a magnet with its armature, a pivoted bar carrying said armature and a dog pivoted to said carrying-bar adapted to engage the last-named ratchet-wheel, substantially as described. 60
- 15 11. In an electric-railway switch, the combination with the switch-tongue, a pin depending from said tongue, a cross-arm rigidly mounted on said pin, arms pivotally connected with said cross-arm and spring-yokes connected respectively to the last-named arms, a dog and a slotted plate mounted on the other ends of the respective yokes, of a train of integral ratchet-wheels, two of which have teeth cut to alternate and adapted to be engaged by the dogs on the resilient yokes, said slotted plates working on the axis of said train, an operating-dog coöperating with the other ratchet-wheel, and pivoted arm on which said dog is mounted, said armature being secured to the above-named carrying-bar, substantially as described. 70
- 20 12. In an electric-railway switch, the combination with the switch-tongue, of a train of integral ratchet-wheels with teeth cut to alternate, dogs adapted to engage said train, a resilient connection between the switch-tongue and said dogs, an integrally-operating ratchet-wheel, a pivoted carrying-bar provided with a dog pivotally mounted on the same and adapted to engage the operating ratchet-wheel, a magnet and its armature, said armature being mounted on said carrying-bar, substantially as described. 75
- 25 80
- 30 85
- 35 90
- 40 95
- 45 100

ELISHA MOORE.
